PORTABLE CARTRIDGE TAPE PLAYER

Takeshi Sasaki, Tokyo, Japan, assignor to Motorola,
Inc., Franklin Park, Ill.

Filed Jan. 7, 1970, Ser. No. 20,800

Term of patent 14 years

Int. Cl. D14—01

U.S. Cl. D26—14

FIG. I

FIG. 4

FIG. 5

FIG. 1 is a perspective view of a portable cartridge tape player showing my new design;

FIG. 2 is an end view as seen from the right hand side in FIG. 1; the other end view being visible in FIG. 1;

FIG. 3 is a rear side elevation view with respect to FIG. 1, the front side elevation view being shown in the perspective view;

FIG. 4 is a front elevation view of the left hand portion of the tape player shown in FIG. 2 with the same being opened and removed from the right hand portion thereof the rear elevation view being shown in FIG. 1; and

FIG. 5 is a front elevation view of the right hand portion of the tape player shown in FIG. 2 with the left hand portion being removed therefrom the rear elevation view being shown in FIG. 3.

The grille member is understood to continue uniformly throughout the rectilinear areas disclosed in FIGS. 4 and 5.

I claim:

The ornamental design for a portable cartridge tape player, as shown and assembled.
